[57] **CLAIM**

The ornamental design for a cane-functioned collapsible chair, as shown and described.

DESCRIPTION

FIG. 1 is a perspective view of a cane-functioned collapsible chair showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

FIGS. 2 through 7 have been shown on a reduced scale with respect to FIG. 1.

The fragmented surface treatment shown on the seat is understood to be continuous throughout the implied area.

The broken lines shown on the seat represent stitching.
